UNITED STATES PATENT OFFICE.

FRED P. MUEHLENBECK, OF CHICAGO, ILLINOIS, ASSIGNOR TO EUGENE C. GMELIN,
OF CHICAGO, ILLINOIS.

HEATER.

Application filed February 11, 1925. Serial No. 8,475.

This invention relates to improvements in heaters. The invention is here shown as embodied in a heater especially adapted for industrial uses such as for drying enamels, 5 paints, lacquers and the like, baking castings, ovens, laundries, can dryers, wire dryers, and so forth.

My improved heater is especially adapted for producing recirculation thus saving fuel.

10 By the use of my heater it is possible to produce recirculation in ovens where japan, paint, lacquer, and varnishlike products are to be dried. Recirculation in such ovens has heretofore been considered impossible 15 or quite dangerous due to the fire hazard and the ever-present explosive gases. In drying such products combustible gases are liberated in the process of drying. It has been found that the sooner these vapors are carried away and destroyed, the quicker the 20 drying is effected. My improved heater is so designed that it may be made an integral part of a vapor utilization system with complete combustion of the gas fuel taking place 25 in the first combustion chamber which is made of circular baffle brick. Beyond the first combustion chamber there is a second combustion chamber built of rectangular fire brick placed horizontally and vertically.

30 The combustible vapors and the excess air required to burn them are introduced into the heater so that they mingle with the burning gases as they pass from the first combustion chamber to the second. At this point

35 the products of combustion of the gas fuel have attained substantially their highest temperature. Thus, the fresh air and the combustible gases meeting the burning gases, makes it impossible for any dangerous 40 vapors to pass without being instantly consumed. Because of this construction, it will be seen that the heater converts any dangerous combustible gases into productive heat and in addition eliminates all danger of fire 45 or explosion within the oven. This follows from the fact that the combustible vapors are consumed substantially as rapidly as they form.

An observation window is provided on 50 the heater in order to observe the degree of combustion at all times, thus enabling the operator to increase or decrease the air sup-

ply accurately. The window is placed where combustion should be entirely completed.

The heater is also equipped with an automatic gas shut-off.

The above mentioned features, and other features and advantages of my invention will appear more fully and be described more in detail as I proceed with my specification.

In that form of device embodying the features of my invention shown in the accompanying drawings, Figure 1 is a view in side elevation of the heater, Fig. 2 is a top plan view of the same, Fig. 3 is a view in end elevation, Fig. 4 is an enlarged view showing in detail a part of the automatic shut-off, Fig. 5 is a vertical sectional view, Fig. 6 is a view taken as indicated by the line 6 of Fig. 5, Fig. 7 is a view taken as indicated by the line 7 of Fig. 5, Fig. 8 is a view taken as indicated by the line 8 of Fig. 5, Fig. 9 is a view taken as indicated by the line 9 of Fig. 5, and Fig. 10 is a view partly in side elevation and partly in section showing the heater connected to a drying oven.

In that form of device embodying the features of my invention shown in the accompanying drawings, 10 indicates a substantially rectangular casing or shell provided with the spaced inner and outer walls 11 and 12 respectively having between them any suitable non-combustible insulating substance, as, for example, clay, as indicated by 13.

In one end of the casing 10 there is provided a smaller axially arranged rectangularly casing 14 made of sheet metal or other suitable material and constituting a first combustion chamber. The casing 14 is lined with suitable refractory material such as fire brick 15 provided with inwardly projecting staggered alternately vertically and horizontally arranged projecting lugs 16, 16 in order to better mix the gases to be burned and in order to give the products of combustion a tortuous passage therethrough. 17 indicates a jet or nozzle through which the fuel is admitted such as illuminating gas, natural gas, or other inflammable gas. Surrounding the nozzle 17 are a series of air inlets 18 adapted to be opened or closed as desired by the rotatable shutter 19 so that

the desired proportion of gas and air can be admitted into the first combustion chamber 14. 20 indicates a pipe leading to the nozzle 17 through which the gas to be burned 3 is conducted.

At the discharge end of the heater there is provided a blower or fan 21 which may be of any desired form and adapted to cause a circulation through the heater, so that 10 gases and products of combustion in the heater will be drawn through the same from left to right as viewed in Fig. 1 and Fig. 5. The discharge outlet from the fan 21 is connected to a conduit 22 which leads to the 15 bottom of an oven 23 as shown in Fig. 10.

In Fig. 10, the arrows indicate the travel of the heated gases and products of combustion coming from the heater. Within the oven 10 there may be provided any suitable 20 means such as the wire mesh shelves 24 for supporting the articles to be dried as indicated by 25. 26 indicates a conduit leading from the top of the oven to the heater 10. As clearly shown in Fig. 5, the conduit 26 25 enters the top of the heater 10 above the inner combustion chamber 14 which is made smaller than the shell 11 thus affording a space 27 between the two.

Beyond the end of the first combustion 30 chamber 14 there is in the heater 10 what may be termed the second combustion chamber as indicated by 28. Within this chamber there are provided staggered alternately arranged vertical and horizontal baffle bricks 35 29 in order to better commingle the inflammable gases.

Where the conduit 26 enters the heater there is provided a damper 30 which may be adjusted to regulate the flow of gases there- 40 through. At the lower side of the heater substantially opposite the point where the conduit 26 enters there is provided a fresh air inlet 31 provided with a regulating damper 32.

45 In the operation of the device, gas and air are admitted at 17 and 18 in order to give an inflammable mixture which is ignited and burns within the first combustion chamber 14 issuing from the right end thereof (as viewed in Fig. 5). The fan 21 operates to cause a suction of air through the ports 18 and also operates to cause a circulation through the heater as explained before. The 50 products of combustion acting as a drying medium are exhausted from the heater by the fan 21 and blown into the oven 23 at the bottom whence they pass upwardly through the oven drying the articles 25. In cases where the articles 25 have been painted with 55 lacquer, enamel, paint, or other substances so that during the drying process they give off combustible vapors, the following operation takes place. These combustible vapors are drawn out of the oven at the top through 60 the conduit 26 and enter the heater into

the space 27 around the first combustion chamber. The combustion in this first chamber has heated the outer walls of it and consequently these combustible vapors entering through the conduit 26 into the space 27 70 become heated. The draft through the heater caused by the fan draws these combustible vapors into the second combustion chamber 28 where they become mixed with the burning gases issuing from the first combustion chamber; and thus they are ignited and burned in the second combustion chamber. Any additional fresh air required to aid in combustion is admitted through the fresh air inlet 31 by means of the valve 32. 80 The baffle bricks 29 in the second combustion chamber 28 cause a thorough mixing of the combustible vapors and gases entering the heater through the conduit 26 with the burning gases issuing from the first combustion 85 chamber 14 so that such combustible gases and vapors coming from the oven are completely burned up and thus all danger of explosion removed. The burning of these combustible vapors also furnishes additional 90 heat to the drying medium issuing from the heater and consequently aids in the drying process and also effects a saving of fuel.

There is also provided an automatic shut-off for the gas, and the construction and operation of this device will now be explained. Near the discharge end of the heater 10 there is provided a swingable plate or vane 33 hinged at its upper edge on a mounting member as indicated by 34. This vane, when the heater is not in operation, hangs in a vertical position as shown in Fig. 5. The vane is light enough, however, so that when the heater is in operation, it will be swung up into the substantially horizontal position at 100 the top of the heater as shown in Fig. 4 by the flow of the gases through the heater. The upper edge of the vane 33 is pivoted by means of a shaft 34 extending through the heater. One end of this shaft outside of the heater is provided with a short lug 35 which takes a vertical position as shown in Fig. 4 when the vane is swung up against the top of the heater. On the pipe 20 carrying the gas to the heater there is provided a quick 105 acting valve 36 controlled by a lever 37. To the end of the lever 37 there is attached a handle 38 and this lever 37 is also pivoted at 39 to the upper end of a piston rod 40 connected to a plunger in a dash pot 41 which may be of any suitable construction. At 39 there is also pivoted a long arm 42 having at one end a notch 43 adapted to be engaged by the lug 35 on the shaft 34. This notch 43 is so spaced that it will be thus engaged only when the handle 38 is raised sufficiently to move the lever 37 to open the valve 36. When the lever 37 is down in substantially horizontal position as shown in Fig. 1, the valve 36 is closed. It is obvious that rais- 110 115 120 125 130

ing the handle 38 to lift the lever 37 to open the valve 36 also raises the left end of the arm 42 placing it in the position as shown in Fig. 4 to draw the notch 43 to the left 5 until it is engaged by the lug 35 as shown in Fig. 4.

In the operation of the device, the fan is started first. The velocity of the gases through the heater swings the damper or 10 vane 33 from its vertical position to a horizontal position against the top of the heater. The handle 38 is then raised opening the quick acting valve 36 and this valve is held open by engagement of the notch 43 with 15 the lug 35. The gas issuing from the nozzle 17 is then lighted and the proper air adjustment given by regulation of the shutter 19. A window 44 is provided near the discharge end of the heater in order to observe 20 the combustion. The damper 32 is regulated to admit any fresh air as desired in order to make complete combustion in the heater. If for any reason the fan should cease to operate, the damper 33 will fall, 25 thus releasing the lug 35 from the notch 43 allowing the handle 38 to descend and close the gas valve 36. The dash pot 41 is provided in order to cushion the downward movement of the handle 38.

30 While I have shown and described certain embodiments of my invention, it is to be understood that it is capable of many modifications. Changes, therefore, in the construction and arrangement may be made 35 without departing from the spirit and scope of the invention as disclosed in the appended claims, in which it is my intention to claim all novelty inherent in my invention as broadly as possible in view of the prior art.

40 What I claim as new, and desire to secure by Letters Patent, is:

1. An apparatus of the character specified having an endless passage therein, a blower for circulation of air in said passage, a

burner within the passage, means of fuel 45 supply for the burner subject to the suction of the blower, a vane in said passage movable to and adapted to be held in open position by the action of the blower, a cut-off valve in said means adapted for manual 50 opening independently of the vane and normally seeking a closed position, and a connecting means between said valve and vane to automatically engage the vane through opening movement of the valve to hold the 55 valve against closing influence.

2. In an apparatus of the character specified, a vane therein held in open position by pressure within the apparatus, a fuel supply pipe for the apparatus having a cut-off 60 valve, means operable manually to open the valve independently of the movement of the vane, comprising a lever connected to the valve, an arm member connected to the lever, said vane having a mounting member 65 across which the arm member slides during said movement, one of said members having a lug and the other member having a notch adapted to engage through said movement to hold the valve against closing influence. 70

3. In an apparatus of the character specified, a vane therein held in open position by pressure within the apparatus, a fuel supply pipe for the apparatus having a cut-off 75 valve, means operable manually to open the valve independently of movement of the vane, an arm member connected to said means, said vane having a mounting member across which the arm member slides during said movement, and interengaging 80 means on said members disengaged when said vane is closed and being engageable through said movement to hold the valve against closing influence.

Witness my hand this 9 day of February, 1925.

FRED P. MUEHLENBECK.
